(57) **CLAIM**

The ornamental design for a spa shell as shown and described.

DESCRIPTION

FIG. 1 is a perspective view of a spa shell showing our new design;

FIG. 2 is another perspective view thereof;

FIG. 3 is a top plan view thereof;

FIG. 4 is a cross-sectional view thereof, taken in the direction of line 4-4 of FIG. 3;

FIG. 5 is a cross-sectional view thereof, taken in the direction of line 5-5 of FIG. 3;

FIG. 6 is a cross-sectional view thereof, taken in the direction of line 6-6 of FIG. 3;

FIG. 7 is a cross-sectional view thereof, taken in the direction of line 7-7 of FIG. 3;

FIG. 8 is a cross-sectional view thereof, taken in the direction of line 8-8 of FIG. 3;

FIG. 9 is a cross-sectional view thereof, taken in the direction of line 9-9 of FIG. 3;

FIG. 10 is a cross-sectional view thereof, taken in the direction of line 10-10 of FIG. 3;

FIG. 11 is a cross-sectional view thereof, taken in the direction of line 11-11 of FIG. 3;

FIG. 12 is a cross-sectional view thereof, taken in the direction of line 12-12 of FIG. 3; and,

FIG. 13 is a cross-sectional view thereof, taken in the direction of line 13-13 of FIG. 3.

Dash-dash broken lines in the drawings illustrate portions of the spa shell that form no part of the claimed design. The dash-dot-dash broken lines illustrate the line from which the cross-sectional views are taken and form no part of the claimed design.
